UNITED STATES PATENT OFFICE.

THOMAS WATERS, OF NORTHAMPTON, ENGLAND.

MACHINE FOR USE IN REPAIRING BOOT AND SHOE SOLES.

1,250,057.

Specification of Letters Patent. Patented Dec. 11, 1917.

Application filed June 4, 1917. Serial No. 172,781.

To all whom it may concern:

Be it known that I, THOMAS WATERS, a subject of the King of England, residing in Northampton, in the county of Northampton, England, have invented certain new and useful Improvements in Machines for Use in Repairing Boot and Shoe Soles, of which the following is a specification.

This invention relates to the repairing of boots and shoes and has for an object to provide an improved method and means whereby a worn sole may be severed and beveled at the joint or other place in order to allow a fresh sole piece to be applied to the boot. In doing repairs of the nature indicated upon ordinary boots the cut, which is generally at the joint, is usually made as nearly as possible in the line of the bevel with a hand knife. Severing in this way, however, becomes impossible when the work to be treated contains any considerable quantity of metallic fasteners or reinforcements such as are present in military boots, and in such work the removal of the worn sole and the beveling of the remaining portion to the proper angle to receive the new sole piece is, with the methods hitherto in use, laborious and occupies considerable time.

According to the present invention the sole is severed and the desired bevel surface produced on the remaining part of the sole simultaneously with such severing (unless the severing has previously been performed by other means) by cutting through the work perpendicularly, or approximately so, toward the required bevel surface, thereby removing a portion of the sole, by relatively traversing the work and a rotary power driven tool.

Conveniently the work and tool are relatively traversed a number of times, the tool removing at each traverse a certain amount of material, which amount will depend upon the toughness of the work and upon the pressure applied between the tool and the work, until the sole is severed and the desired bevel is produced.

Additional features of the present invention reside in certain constructional features of apparatus hereinafter described.

A preferred form of apparatus for carrying the invention into effect will now be described by way of example. In this apparatus the work is presented to and traversed across the tool. It will be understood, however, that in an alternative construction the

work may be fixed and the tool presented thereto and traversed across it.

In the accompanying drawings:

Figure 1 shows in plan the upper portion of a machine constructed in accordance with the present invention;

Fig. 2 is a side elevation of the same; and Figs. 3, 4, 5 and 6 are detail views of parts of the machine shown in Figs. 1 and 2.

Like reference characters indicate like parts in all the figures.

The apparatus comprises a rotary cutting tool 1, conveniently mounted on a horizontal shaft 2 adapted to be rotated from any suitable source of power, and a work holder of which the main member is an open frame 3 universally pivoted at one end to a supporting post 4 on the table of the machine (there being horizontal and vertical pivots 5 and 6 respectively) and provided at the other end with a handle 7 by which the work is brought by the operator by a horizontal movement into contact with the tool and is by a vertical movement traversed across the rotary tool. The boot of which the sole is to be cut through is held inside a secondary frame 8, mounted within the frame 3 first mentioned, and having its end nearest the rotary cutter curved on its inside (see the surface 9) to the normal side-to-side curve of a worn boot sole and provided with a slot 10 slightly wider than the tool and of a length greater than the width of the largest sized boot required to be treated. The outside 11 of the slotted end of the secondary frame is shaped approximately to the usual curve of the inner side of the sole to be cut through and co-operates, as will be hereinafter explained, with a gage for the depth of cut. The boot is positioned with its sole against the inside of the slotted end of the secondary frame in the following way:

A last is inserted in the boot and in the usual pin hole is placed the short leg 12 of a bar bent at right angles, the longer leg 13 of this bar extending over the forepart of the boot. In the end of the secondary frame opposite the slot is mounted a screw 14 carrying at one end a hand adjusting wheel 15, and at the other a member 16 containing a hole for the reception of the long leg 13 of the aforementioned bent bar. The boot is placed by the operator with the portion of its sole which requires to be beveled over the slot and is then firmly positioned there

22
by screwing the hand wheel so as to force the longer leg of the bent bar toward the last.

- In operation, the main frame 3 carrying 5 the secondary frame 8 with the boot positioned therein is swung around by hand on its pivot 6 which is placed so that the tool will pass into the slot in the secondary frame when the work holder is moved around.
- 10 The cutting of the sole is done by traversing the frame (while pressing it against the tool) the required number of times past the cutter by moving it up and down on its pivot 5.
- 15 In order to make an adjustment in the angle of the bevel formed on the remaining portion of the original sole, the secondary frame may be arranged to pivot within the main frame, preferably on pivots 17 lying 20 approximately in the line of that side of the slot nearest to the pivoted end of the main frame, so that the slot maintains a constant lateral position with relation to the tool in spite of the adjustment. Suitable means 25 such as slot 18, screw 19 and fly nut 20 are provided for clamping the frame 8 in adjusted position on the frame 3. The main frame may conveniently carry a lug 21 which may be dropped into a recess 22 formed on the supporting post 4 so that the boot-carrying frame may (when moved out of position by lifting the frame to bring the lug 21 over the flange 23 in which the recess is formed, until the lug and recess 30 are in line) rest supported away from the tool out of use and while a boot is being inserted or removed.
- In order to regulate the total depth of cut to be made there is mounted on the bearing 40 of the tool shaft 2 and close to the side of the tool a guard or gage 24 which can be set to contact, when the cut has been made to the required depth, that is, when the sole has been severed without cutting into any underlying portion 45 of the work, with the outside of the secondary frame adjacent the slot. Since, however, the curvature from side to side of boots varies it is found necessary in a good 50 many cases to cut a little deeper, particularly at each side, than the curvature of the outside of the slotted end of the secondary frame would permit, and consequently, the guard is preferably held yieldingly in its 55 normal position (by a spring 25 forcing it against the adjustable stop 26) and can be forced backward by the operator as he presses the work holder toward the tool should he find it necessary to cut deeper at 60 any particular place. The amount which this guard may be forced back is preferably limited by an adjustable stop consisting of a wedge block 27 adapted to coact with an inclined surface 28 on the rear of the guard block.

The tool employed is conveniently about $\frac{3}{4}$ " to 1" wide (this being the average width of bevel required) and is preferably in the form of a milling cutter of high grade steel that is not affected by contact with metallic fasteners of the kind general in military boots such as standard screws, "slugs" or "bills". Alternatively a grinding cutter, as of emery, may be employed. There is preferably embodied in the ma- 75 chine a suction fan of usual type to draw away the particles removed by the rotary tool.

As hereinbefore indicated the tool is shaped so as to simultaneously sever the sole 80 and leave the remaining portion thereof correctly beveled by removing a portion from the sole. This portion is in cross section longitudinally of the boot a triangle with its base, which is its shortest side, approximately perpendicular to the sole of the boot, one of the two longer sides of the triangle representing the beveled surface of the remaining portion of the sole. Thus if the boot is positioned with the surface of the sole approximately parallel to the axis of the cutter, the cutting edge will be at an angle to such axis, equal to the normal angle of bevel required, that is the tool will be frusto conical. A guard is also preferably 85 provided to insure that the cut produced by the tool is a clear bevel running out on to the surface; this may conveniently take the form of a disk 29 mounted on the cutter shaft against the smaller end of the tool. 90 95 100

As has been above indicated the above described method of severing and beveling soles is particularly useful with work containing considerable quantities of metallic fasteners but it possesses advantages of 105 speed in cutting and accuracy of beveling for ordinary work.

Cutting in the direction specified (i. e., removing from the work successive portions each of which is nearer to the desired bevel surface than the preceding portion) as against cutting along the desired bevel surface is of advantage in that the tendency which obstructions in the work would have to displace the tool from the desired line of 115 cut is avoided.

What I claim as my invention and desire to secure by Letters Patent is:—

1. In a machine for use in repairing boot and shoe soles, the combination of a milling cutter, means for rotating the cutter, means at one side of the cutter for supporting a boot or shoe with its sole directed toward the cutter, and means for effecting relative movement between the cutter and boot support to cause the cutter to form a cut transversely of the sole of a boot or shoe supported by said support, severing the sole to permit a portion thereof to be removed, the wall of said cut on the part of the sole por- 120 125 130

tion to remain attached to the body being beveled.

2. In a boot or shoe repair machine, the combination of a cutter, a boot or shoe support comprising a main frame mounted to have a universal movement, a secondary frame adjustably mounted in the main frame, and provided with an abutment against which the sole of a boot or shoe 10 is adapted to bear, said abutment being slotted to permit the cutter to engage the sole of a boot or shoe, means for holding a boot or shoe in position with its sole extending across the slot in said secondary 15 frame, and means for moving the boot or shoe support to and from the cutter and in a path transverse to the cutting surface, for the purpose described.

3. In a boot or shoe repair machine, the combination of a power actuated cutter, means adapted to receive and support a boot or shoe and including an abutment or surface against which the sole of the boot or shoe will bear, said abutment being slotted 25 to permit the cutter to engage said sole, and means for effecting relative movement between the cutter and the boot or shoe supporting means, for the purpose described.

Copies of this patent may be obtained for five cents each, by addressing the "Commissioner of Patents.
Washington, D. C."

4. In a boot or shoe repair machine, the combination of a milling cutter, means for supporting a boot or shoe comprising an abutment for the sole thereof having a slot through which the cutter may operate, and means for moving the boot or shoe support to and from the cutter and effecting relative 30 transverse movement between said parts, for the purpose described.

5. In a boot or shoe repair machine, the combination of a milling cutter, means for supporting a boot or shoe comprising an 40 abutment for the sole thereof having a slot through which the cutter may operate, means for effecting relative movement between the boot or shoe supporting means and the cutter, whereby a cut having a beveled wall will 45 be formed transversely of the sole of the boot or shoe, and means for effecting adjustment of the boot or shoe to vary the angle of said beveled wall.

In testimony whereof I have signed my 50 name to the specification in the presence of two subscribing witnesses.

THOMAS WATERS.
